UNITED STATES PATENT OFFICE.

NORMAN MARSHALL, OF NEWTON, MASSACHUSETTS.

MACHINE FOR MAKING LAMP-BASES.

No. 856,974.

Specification of Letters Patent.

Patented June 11, 1907.

Application filed November 9, 1906. Serial No. 342,624.

To all whom it may concern:

Be it known that I, NORMAN MARSHALL, a citizen of the United States, and a resident of Newton, Massachusetts, Middlesex county, have invented certain new and useful Improvements in Machines for Making Lamp-Bases, of which the following is a specification.

The invention relates to machines for manufacturing bases for incandescent lamps in which the outer shell and center terminal or contact are united by a web of glass or other fusible insulating material,

It is the purpose of the invention to provide a simple and efficient mechanism for automatically feeding and introducing the outer shells into the molds or receptacles in which the molding or shaping of the insulating material of the base is effected.

The various features of the invention will be understood from the following detailed description of the mechanisms in which I have embodied them and will be set forth in the claims.

In the accompanying drawings—Figure 1 is an elevation of so much of a lamp base making machine as is necessary to an understanding of the present invention. Fig. 2 is an enlarged sectional detail showing the construction of mold and the manner of supplying molten glass or other insulating material thereto. Fig. 3 is a plan view showing the mold carrier and operating mechanism therefor and the mechanism for feeding the shells to the molds, the glass furnace and molding mechanism being omitted for the sake of clearness. Fig. 4 is a plan view of the hopper for the base shells. Fig. 5 is an elevation showing the devices at the lower end of the feed chute for the shells. Fig. 6 is a plan view showing the end of the feed chute. Fig. 7 is a vertical sectional view showing the devices for transferring the shells from the end of the feed chute to the molds. Fig. 8 is a transverse sectional view through the feed chute for the shells. Fig. 9 is a sectional view showing the metallic shell for the lamp base; and Fig. 10 is a view showing the center contact for the lamp base.

In the machine shown in the drawings a series of molds or receptacles **A** shaped to receive the outer shell and center contact of the lamp base and to hold them in proper relation to each other, are mounted upon a rotary carrier **A'** and by the movement of this carrier each mold is brought into position to

receive the center contact, then into position to receive the outer shell, then into position beneath the discharge outlet from the glass furnace, then into position beneath the molding devices, and finally into position where the completed base is removed from the mold.

The rotary carrier **A'** may be given the proper intermittent movements to bring the molds successively into position for the various operations, by any suitable operating mechanism, and in the construction shown is given such movements by means of a crank pin **A²** carried by a constantly rotating shaft 65 and arranged to engage radial slots **A³** formed in a disk which is secured to the shaft **A⁴** upon which the carrier is mounted. The shaft **A⁵** to which the crank pin **A²** is secured is also provided with a segmental locking disk **A⁶** 70 which co-operates with segmental locking surfaces **A⁷** formed on the slotted disk, the engagement of the segmental disk **A⁶** and surfaces **A⁷** acting to lock the mold carrier in position between successive movements. 80

The molds may be of any suitable construction and are conveniently constructed as shown in Fig. 2. As shown in this figure the mold consists of a cylindrical tube **a** secured to the carrier **A'**, the tube being of 85 proper size to receive the metallic outer shell of the lamp base and forming the outer walls of the mold. The bottom of the mold is formed by the upper end of a plunger **a'** which is recessed at **a²** to receive the center 90 contact and retain it in proper position and is also recessed at **a³** to receive the lower end of the shell. The plunger **a'** is provided with a flange **a⁴** and is held in normal position by means of a spring **a⁵** introduced between the 95 flange **a⁴** and the fixed plate **a⁶** which carries the tube **a**. The plunger **a'** is supported against the tension of the spring by engagement with a bar **a⁷** extending across the opening in the carrier **A'** within which the plunger 100 is mounted, and the plunger is guided upon a fixed stud **a⁸** secured to the carrier **a'** and extending up within the plunger. With this construction the plunger **a'** acts to support the parts during the forming of the base and 105 may then be raised against the tension of the spring to eject the finished base from the mold.

The center contacts for the bases are of the form shown in Fig. 10 and consist of a thin disk **5** having a hollow stem **4** which is provided with an outwardly flaring upper

end. The contacts may be introduced into the recesses a^2 of the receptacles as they come successively into convenient position for such operation either by an operator or by automatic mechanism not shown.

The molds or receptacles are carried by the carrier A' from the position where they receive the center contacts to position where the metallic shells are automatically introduced. In the form of base which the machine being described is designed to manufacture these shells consist of thin brass cylinders corrugated to form screw threads and provided with a curved inwardly projecting flange 2 at their lower ends.

The shells are delivered into position to be introduced into the molds by a feed chute C beneath the lower end of which the molds are successively brought by the movements of the carrier. The shells are supplied to the feed chute C from an inclined hopper C' arranged at the upper end of the inclined chute and provided around the lower edge of its periphery with a series of openings C² so shaped that the shells may pass through the openings, provided they register therewith in proper relation, that is to say with the curved lower end of the shell resting against the bottom of the hopper. The bottom of the hopper is stationary, while the cylindrical part of the hopper within which the recesses C² are formed is constantly rotated by means of a belt C³ passing about the outer periphery of the hopper. As the hopper revolves the shells within the hopper are agitated and carried up to a greater or less extent by frictional engagement with the walls of the hopper and certain of the shells will properly register with the openings C² and pass through said openings as the hopper revolves. These shells will pass into the upper end of the feed chute and slide down said chute, forming a series of shells extending to the lower end of the chute, the end shell of the series resting against a fixed stop C⁴ at the end of the chute.

The lower edge of the hopper is surrounded by an upwardly projecting flange C⁵ which extends about the greater portion of the hopper and prevents the escape of the shells through the openings C². At that portion of the hopper which is adjacent to the upper end of the feed chute and which is traveling upward from the lower edge of the hopper, the flange C⁵ is arranged at a distance from the periphery of the hopper sufficient to allow the passage of the shells through the openings C² as indicated in Fig. 4. As the openings C² in the lower edge of the hopper pass opposite this part of the flange C⁵, any shells which may have entered the openings slide downward through the openings into the guideway C⁶ formed between the flange C⁵ and the outer periphery of the hopper, and slide down this guideway into the

upper end of the feed chute C. In order to avoid injury to the shells in case they are carried up between the flange C⁵ and the traveling periphery of the hopper, or in case they pass but partially through the opening C², the upper part of the flange C⁵, which extends inward toward the periphery of the hopper at the upper end of the guideway C⁶, is made yielding. In the form shown this portion C⁷ of the flange C⁵ is formed of spring metal which curves inward from the rigid part of the flange C⁵ which forms the outer wall of the guideway C⁶ and forms a yielding cam surface for forcing the shells which have passed but partially through the openings C² back into the openings as they pass upward toward the upper part of the hopper.

The feed chute C is so arranged that the shell which is in position against the fixed stop C⁴ is directly above one of the molds A during the interval between the successive movements of the mold. When in this position the shell is supported by two spring fingers C⁸ and is directly beneath a vertically reciprocating plunger C⁹ the downward movement of which carries the shell from the end of the feed chute down into the mold, the spring fingers C⁸ yielding to accommodate the downward movement of the shell and assisting in maintaining the shell in proper alignment with the mold. The lower end of the plunger C⁹ is shaped to enter the shell and is also recessed to embrace the stem 4 of the center contact as the plunger completes its downward movement. The plunger is mounted in the head C¹⁰ carried by the bracket B¹⁹ and its upper end is bifurcated to receive a cam C¹¹ secured to the shaft B²⁰. The plunger carries the roll C¹² which is held in engagement with the cam by means of spring C¹³ and the plunger is slotted at C¹⁴ for the passage of the cam shaft. The plunger C⁹ is advanced and retracted during the interval between successive movements of the mold carrier.

After the center contact and shell have been introduced and positioned in the mold as above described the mold is brought by the continued advance movements of the mold carrier, into position below the discharge orifice E of the glass furnace E' as indicated in Fig. 2, and the movements of the mold carrier are so timed with relation to the discharge of glass from the furnace that the proper amount of glass is delivered to the mold during the time that it remains beneath the discharge orifice. After the glass has thus been supplied to the mold, the mold is brought by the movement of the mold carrier, into position below the molding plunger F and stripping plate F'. The molding plunger and stripping plate are carried upon two reciprocating rods F² F³ which are operated at proper intervals by suitable mechanism not shown.

After the molding has been performed and the stripping plate and molding plunger returned to normal position, the mold is advanced and is brought by the movement of the mold carrier into position above the ejector pins G, indicated in Fig. 1. These pins are reciprocated at proper intervals by mechanism not shown and as they rise they pass up on opposite sides of the bar a⁷ and act against the flange a⁴ to force the plunger a' of the mold upward against the tension of the spring a⁵, thus forcing the completed base up out of the mold where it may be knocked off of the upper end of the plunger by an air blast or in any suitable manner.

Without attempting to set forth in detail the various modifications and changes which may be made in the mechanisms without departing from my invention, what I claim and

desire to secure by Letters Patent is:—

1. A machine for making lamp bases having in combination a receptacle for the base parts, a feed chute for the shells having its delivery end arranged to register with the receptacle, yieldingly mounted supports at the delivery end of the feed chute, a reciprocating plunger for transferring the shells from the supports to the receptacle, means for supplying an insulating compound to the receptacle, and means for shaping the compound.

2. A machine for making lamp bases having in combination, a receptacle for the base parts, a feed chute for the shells having its delivery end arranged to register with the receptacle, supporting fingers arranged at the delivery end of the feed chute, a reciprocating plunger shaped to enter the shell, and carry it downward past the supporting fingers, means for supplying an insulating compound to the receptacle, and mechanism for shaping the compound.

3. A machine for making lamp bases having in combination a rotary hopper mounted upon an inclined axis, a series of openings in the lower edge of the hopper corresponding in shape to the shape of the shells, a guideway into which said openings deliver, and a feed chute forming a continuation of the guideway.

4. A machine for making lamp bases having in combination a rotary hopper mounted upon an inclined axis, a series of openings in

the lower edge of the hopper corresponding in shape to the shells, a guideway partially surrounding the hopper into which said openings deliver and provided with a wall which approaches the periphery of the hopper and acts as a cam surface for forcing the shells back into the recesses as they pass up the guideway.

5. A machine for making lamp bases having in combination a rotary inclined hopper, a series of openings in the lower edge of the hopper corresponding in shape to the shape of the shells, a guideway partially surrounding the hopper into which the openings deliver, a yielding wall for the guideway which approaches the periphery of the hopper and acts as a yielding cam surface for forcing the shells into the openings as they pass up the guideway.

6. A machine for making lamp bases having in combination a receptacle for the base parts, a feed chute for the shells having its delivery end arranged to register with the receptacle, yieldingly mounted supports at the delivery end of the feed chute, and a reciprocating plunger for transferring the shells from the supports to the receptacle.

7. A machine for making lamp bases having in combination a receptacle for the base parts, a feed chute for the shells having its delivery end arranged to register with the receptacle, supporting fingers arranged at the delivery end of the feed chute, and a reciprocating plunger shaped to enter the shell and carry it downward past the supporting fingers.

8. A machine for making lamp bases having in combination a receptacle for the base parts provided with a recess for the center contact and a seat for the shell, a feed chute for the shells having its delivery end arranged to register with the receptacle, yieldingly mounted supports at the delivery end of the feed chute, and a reciprocating plunger for transferring the shells from the support to the receptacle.

In witness whereof, I have hereunto set my hand, this 7th day of November, 1906.

NORMAN MARSHALL.

In the presence of—

IRA L. FISH,
KATHARINE A. DUGAN.
